(57) **CLAIM**

The ornamental design for a filing cabinet, as shown and described.

DESCRIPTION

FIG. 1 is a front, top perspective view of a first embodiment of a filing cabinet, showing my new design;

FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is an enlarged view of detail "9" identified in FIG. 1;
FIG. 10 is an enlarged view of detail "10" identified in FIG. 1;
FIG. 11 is an enlarged view of detail "11" identified in FIG. 1;
FIG. 12 is an enlarged view of detail "12" identified in FIG. 2;
FIG. 13 is a front, top perspective view of a second embodiment of the filing cabinet;
FIG. 14 is a rear, bottom perspective view thereof;
FIG. 15 is a front view thereof;
FIG. 16 is a rear view thereof;
FIG. 17 is a left side view thereof;
FIG. 18 is a right side view thereof;
FIG. 19 is a top view thereof;
FIG. 20 is a bottom view thereof;
FIG. 21 is an enlarged view of detail "21" identified in FIG. 13;
FIG. 22 is an enlarged view of detail "22" identified in FIG. 13;
FIG. 23 is an enlarged view of detail "23" identified in FIG. 14;
FIG. 24 is a front, top perspective view of a third embodiment of the filing cabinet;
FIG. 25 is a rear, bottom perspective view thereof;
FIG. 26 is a front view thereof;
FIG. 27 is a rear view thereof;
FIG. 28 is a left side view thereof;
FIG. 29 is a right side view thereof;
FIG. 30 is a top view thereof;
FIG. 31 is a bottom view thereof;
FIG. 32 is an enlarged view of detail "32" identified in FIG. 24;
FIG. 33 is an enlarged view of detail "33" identified in FIG. 24; and
FIG. 34 is an enlarged view of detail "34" identified in FIG. 25.

(Continued)

The dashed lines in the figures illustrate portions of the filing cabinet that form no part of the claimed design. The dash dot dash lines in FIGS. 1, 2, 9, 10, 11, 12, 13, 14, 21, 22, 23, 24, 25, 32, 33 and 34 are for the purpose of illustrating the enlarged views indicators and form no part of the claimed design.

1 Claim, 34 Drawing Sheets
